CLAIM

The ornamental design for an intraoral sensor, as shown and described.

DESCRIPTION

FIG. 1 is a perspective view of an intraoral sensor showing my new design;
FIG. 2 is a front elevational view thereof;
FIG. 3 is a rear elevational view thereof;
FIG. 4 is a right side view thereof;
FIG. 5 is a left side view thereof;
FIG. 6 is a top plan view thereof;
FIG. 7 is a bottom plan view thereof; and,
FIG. 8 is another perspective view thereof.
The broken lines are included to illustrate environmental structure and form no part of the claimed design.
